(57) **CLAIM**

The ornamental design for a pedal for an aircraft as shown and described.

DESCRIPTION

FIG. 1 is a front, right-side, and top perspective view of a pedal for an aircraft showing our new design;

FIG. 2 is a rear, right-side, and bottom perspective view thereof;

FIG. 3 is a front elevational view thereof;

FIG. 4 is a left rear elevational view thereof;

FIG. 5 is a left side elevational view thereof;

FIG. 6 is a right-side elevational view thereof;

FIG. 7 is a top plan view thereof;

FIG. 8 is a bottom plan view thereof; and,

FIG. 9 is a front elevational view thereof, shown in a condition of use.

The dashed broken lines depict portions of the pedal for an aircraft that form no part of the claimed design. The dashed broken lines in FIG. 9 showing a cockpit depict environmental structure that forms no part of the claimed design.
